[57] CLAIM

The ornamental design for an apparel designator, as shown and described.

DESCRIPTION

FIG. 1 is a perspective view of the apparel designator in use. FIG. 2 is an enlarged perspective view of the apparel designator alone.

FIG. 3 is a somewhat reduced top plan view thereof.

FIG. 4 is a bottom plan view thereof.

FIG. 5 is a front side elevation view; and,

FIG. 6 is a rear side elevation view, the right and left side elevation views being the same as the rear side elevation view.

The broken lines in FIG. 1 are for illustrative purposes only and form no part of the claimed design.
